UNITED STATES PATENT OFFICE.

ROBERT A. ILG, OF CHICAGO, ILLINOIS, ASSIGNOR TO ILG ELECTRIC VENTILATING COMPANY, OF CHICAGO, ILLINOIS, A CORPORATION OF LOUISIANA.

VENTILATING APPARATUS.

Application filed August 4, 1924. Serial No. 729,888.

To all whom it may concern:

Be it known that I, ROBERT A. ILG, a citizen of the United States, residing at Chicago, in the county of Cook and State of Illinois, have invented certain new and useful Improvements in Ventilating Apparatus, of which the following is a specification.

This invention relates to ventilating apparatus of the type disclosed in my former Letters Patent No. 1,189,572 dated July 4, 1916 and No. 1,482,398 dated February 5, 1924, such apparatus comprising a rectangular frame mounted in or over an opening 10 in the wall of the building, a series of horizontal gravity closing shutter vanes pivoted in said frame and connected for simultaneous opening and closing movements, and a motor driven fan mounted opposite said vanes and, when in operation, opening the latter by the blast of air created thereby.

It has been found in practice that when the fan is idle, the automatically closing hinged shutters are apt to rattle more or less and become noisy through the influence of the external winds or natural drafts of air from within the room, and the purpose of my present invention is to provide an improvement on ventilating apparatus of this 20 type which will effectively check this annoyance through means by which the shutter vanes, when closed, are automatically locked in closed position, but are released and permitted to open by the blast of air 30 delivered by the fan when the latter is started in operation.

My present invention, its mode of operation and the advantages inhering therein will be readily understood by persons skilled 40 in the art from the following detailed description taken in connection with the accompanying drawings wherein I have shown one practical and approved embodiment of the principle of the invention, and 45 in which—

Fig. 1 is an inner side elevation of the frame and shutters showing my improved locking device in shutter locking position;

Fig. 2 is a vertical section taken on the 50 line 2—2 of Fig. 1;

Fig. 3 is a vertical section, including a fragment of the wall, with the locking device in release position and the shutters open, and also showing the fan and its motor; and

Fig. 4 is an enlarged sectional detail on the line 4—4 of Fig. 1 through the pivot of the locking device.

Referring to the drawing, 5 may be assumed to represent the external wall of a room to be ventilated, the same having an opening 6 formed therein, over which on the outer side of the wall is secured a rectangular metal shutter frame 7. In and between the opposite vertical members of the frame 60 7 are mounted on horizontal spindles 8 a group of shutter vanes 9. These vanes are connected for simultaneous opening and closing movements by levers 10, one arm of each lever lying in a pocket 11 formed on the rear side of the shutter vane and its other arm being pivoted to a vertically disposed link or shift rod 12 lying inwardly of one vertical side wall of the frame 7. To the inner side of the building wall 5 is secured a frame 13 in which is mounted an electric motor 14, the shaft of which carries a direct driven ventilating fan 15.

The shutter mechanism thus far described is identical with that disclosed and claimed 80 in my former Patent No. 1,482,398, above referred to, to which patent reference may be had for a fuller and more detailed description.

As previously stated, it has been found 85 that when the fan is idle and the shutters closed outside winds or interior drafts tending to flow through the opening cause the shutters to rattle and thus become noisy, and, furthermore, lessen the efficiency of the 90 shutters as a closure for the opening guarded thereby; and by my present invention I provide a very simple and efficient automatic locking mechanism which, when the shutters swing to closed position, locks and 95 holds them in such position; but, when the fan is started in operation, is released by the fan, preferably by the blast of air created by the latter, so that the shutters may readily swing to open position to allow the 100 outflow of the current of air drawn off from the room by the action of the fan.

Describing this locking mechanism, in the upper transverse member of the frame 7 is mounted a pin 16 (Fig. 4), on which is 105 rotatably mounted a metal sleeve 17 secured in place by a cap screw 18 entering the free end of the pin 16. Soldered or otherwise secured on the bearing sleeve 17 is a rod 19 formed on one side of its pivot bearing 110

with a depending limb 20 terminating in an outwardly directed locking point or pin 20' that, in the closed position of the shutter vanes illustrated in Figs. 1 and 2, enters 5 a hole 21 in the link or shift rod 12, and on the other side of its pivot bearing with a downwardly inclined shank portion 22 that is riveted, soldered, or otherwise secured to a downwardly and inwardly inclined flat 10 metal strip or vane 23, the outer edge of which lies close to and substantially in contact with the inner surfaces of the vanes 9. The shank 22 and vane 23 are heavier than the arm 20 and its locking point 20' on the 15 other side of the pivot acting as a counter-weight to urge the pin 20' into locking position, so that, when the shutter vanes are closed, the gravity effect of the vane 23 forces the locking point or pin 20' into the 20 hole 21 of the link 12, as shown in Fig. 1, whereby the shutter vanes 9 are locked in closed position.

When the fan is started, however, the blast of air delivered by the latter, striking 25 against the inner surfaces of the closed shutter vanes, is partly caught or pocked beneath the vane 23 of the locking member, causing the same to swing upwardly substantially to the position shown in Fig. 3. 30 This instantly retracts the locking pin or point 20' from the hole in the link 12, and allows the shutters to open and permit the passage of the current of air, as clearly shown in Fig. 2. The instant the fan stops, 35 however, the shutter vanes drop by gravity to closed position, and the vane 23 of the locking device, by its gravity effect, causes the locking point or pin 20' to instantly re-engage with the aperture in the shutter con- 40 trolling link 12.

It will thus be seen that my invention provides a very simple automatically acting device for locking the shutter vanes in their closed position against vibration and rattling, which locking device is released by 45 the blast of the fan, but automatically returns to locking position by gravity the instant the fan ceases to operate.

While I have herein shown and described 50 one simple and practical instrumentality by which the purpose or object of the invention may be carried out, it is manifest that the specific details of structure may be varied from those shown and described without 55 departing from the substance of the invention or sacrificing any of the advantages thereof. Hence, I reserve all such variations and modifications as fall within the spirit and purview of the appended claims.

I claim—

1. In a ventilating appliance, the combination of a frame, a group of shutter vanes hinged in said frame, a fan mounted opposite said vanes and serving to open the latter by the air blast created thereby, means 65 for locking said vanes in closed position, and means actuated by said fan when in operation for releasing said locking means.

2. In a ventilating appliance, the combination of a frame, a group of shutter 70 vanes hinged in said frame, a fan mounted opposite said vanes and serving to open the latter by the air blast created thereby, automatic means for locking said vanes in closed position, and means actuated by the 75 blast of said fan for releasing said locking means.

3. In a ventilating appliance, the combination of a frame, a group of shutter 80 vanes hinged in said frame, a fan mounted opposite said vanes and serving to open the latter by the air blast created thereby, levers connected to said vanes respectively, a link connecting said levers for simultaneous movements, means for locking said link 85 against movement when said vanes are in closed position, and means actuated by the blast of said fan for releasing said locking means.

4. In a ventilating appliance, the combination of a frame, a group of gravity closing shutter vanes hinged in said frame, a fan mounted opposite said vanes and serving to open the latter by the air blast created thereby, levers connected to said vanes respectively, a link connecting said levers for simultaneous movements and formed with a locking hole, a locking pin automatically engaged in said hole when said vanes are in closed position, and means actuated by 100 the blast of said fan for retracting said locking pin.

5. In a ventilating appliance, the combination of a frame, a group of gravity closing shutter vanes hinged in said frame, 105 a fan mounted opposite said vanes and serving to open the latter by the air blast created thereby, levers connected to said vanes respectively, a link connecting said levers for simultaneous movements and formed with a locking hole, and a pivoted locking pin equipped with a counterweight urging said pin into engagement with said hole when the said vanes are closed, said counterweight being raised to retreat said pin 110 by the blast of said fan when the latter is in operation.

ROBERT A. ILG.
